UNITED STATES PATENT OFFICE.

JOSEPH ALFRED GOYER AND LYNN T. LEET, OF MONTREAL, QUEBEC, CANADA.

DISPENSING APPARATUS.

Continuation of application Serial No. 551,301, filed April 10, 1922. This application filed March 8, 1923.
Serial No. 623,746.

To all whom it may concern:

Be it known that we, JOSEPH A. GOYER and LYNN T. LEET, subjects of the King of Great Britain, residing at Montreal, Province of Quebec, Canada, have invented certain and new useful Improvements in Dispensing Apparatus; and we do hereby declare that the following is a full, clear, and exact description of the invention, such as 10 will enable others skilled in the art to which it appertains to make and use the same.

This invention relates to a new and useful dispensing apparatus designed especially for use in connection with a water cooler, 15 and is a continuation of our United States application Serial No. 551,301, filed April 10th, 1922. The general principles underlying the invention are also applicable to a dispenser for heavy fluids, such as syrups 20 and the like.

In using a cooler of the inverted bottle type, the mouth of the bottle, in all operations of filling, crating, and handling in transportation, comes in contact with the 25 hands of the persons performing these operations. When a bottle is finally inverted in the cooler, the mouth which has come in contact with numerous hands is submerged in the water to be consumed. One of the 30 objects of the invention is to avoid such unsanitary conditions.

The invention operates on the principle 35 of the siphon, and includes novel and efficient means for starting the flow of fluid.

For the purpose of illustration, a set of drawings is herewith attached, of which:—

Figure 1 is a vertical section therethrough;

Figure 2 is a vertical section of the siphon 40 starting device;

Figure 3 is a section on the line 4—4 of Figure 2;

Figure 4 is a section on the line 5—5 of Figure 3;

Figure 5 is a vertical section of the upper 45 portion of a modification;

Figure 6 is a detail of Figures 1 and 6; and

Figures 7, 8 and 9 are details of the compressor in different stages of operation.

In the above views in which like reference characters are employed to designate corresponding parts throughout, the stand consists of a plurality of legs 11 upon which 55 is mounted a top or platform 12. A shelf

13 is secured to the legs beneath the platform and supports a cooling device 14. A fluid container 17 of the type in which distilled water is supplied is mounted on the platform 12 and is closed by a stopper 18. 60 A siphon tube 19 passes from the bottom of the container through the stopper and communicates with the cooling chamber in a manner described below. An air passage or vent 20 is formed in the stopper for the purpose of avoiding the creation of a vacuum in the receptacle. This vent consists preferably of a curved tube 21 inserted in the passage, provided with an air filter 22 which may consist of any material through which 65 air can pass and which will not allow the passage of dust particles.

One of the legs 11 terminates below the platform 12 and is provided at its upper end with a plug 23. A union 24 is secured 70 to this end and receives an upwardly extending pipe 25 in which the lower end of a siphon leg 19' is fitted by means of a screw nipple 26 and porous or permeable packing 27. A valve 28 is fitted in the pipe 25 for 75 permanently shutting off the water supply.

The cooling device heretofore referred to 80 comprises a pair of vessels 29 and 30 one within the other. A ring 31 overlies the tops of the vessels, while a cover 32 is seated 85 in the ring. The cover is co-extensive with the cross sectional area of the vessel 30 so that ice may be uniformly distributed within said vessel, thus overcoming the disadvantages of the usual filling openings. The 90 space between the inner walls of these vessels is filled with a heat insulator 33 such as granulated cork. Within the inner vessel is a cooling tank 34 having a cover 35. A nipple 36 communicates with the interior of 95 the tank and is connected to the union 24 by means of an elbow 37 and a nipple 38. A water tight fit is obtained by washers 39 screwed against the elbow and the wall of the vessel 30 by means of nuts 40. The 100 lower portion of the tank is provided with a pipe 41 which passes through the insulated wall to a tap 42. A leak proof arrangement is here provided by means of the washers 43 and nuts 44. A drain pipe 45 105 is provided with the base of the cooler and allows the melted ice to drip on to a drip plate 46 disposed beneath the tap 42 and pipe 45, and inclined towards the bucket 16.

It will be seen by reference to Figures 1 to 110

2
4 that the siphon tube 19 is joined to the leg member 19' by means of a union 47 from which extends a stem 49 in an upward direction. The free end of the stem is formed 5 in the nature of a piston 50 and is surrounded by a tightly fitting slidably cylinder 51 having a closed top 52 and an air vent 53 in its bottom. Between the leg 19' and the union is fitted a valve casing 54 having an 10 intermediate restricted portion 55 one side of which is curved to form a valve seat 56. The end of the casing adjacent the valve seat is formed with a pair of inwardly turned fingers 57 adapted to retain the valve 15 head 58 which is of such configuration as to close the restricted portion 55 when in proper position. This valve is normally open, the valve head being spaced from the seat by gravity. A similar device 59 is provided 20 between the pipe 19 and the union 47, and opens in the direction of the union.

When it is desired to start the flow of liquid, the cylinder 51 is pulled upwardly to create a suction above the piston 50. This 25 suction draws from the container 17 through the pipe 19 and stem 49, at the same time opening the valve 59. The liquid thus drawn and dropping from the union 47 passes the open valve 58 and flows through the pipe 25 and cooler. Once the flow is thus started, it continues by reason of the atmospheric pressure upon the surface of the fluid through the vent 20. The air displaced from the 30 cooling tank 34 during the filling of the latter passes upwardly through the nipple 36, elbow 37, pipe 25 and out of the permeable packing 27. It will therefore be seen that the pipe 25 serves the double function of 35 conveying water from the siphon to the cooling chamber and allowing the air displaced from the cooling chamber to find its 40 way to the atmosphere.

In the modification shown in Figures 5 to 9, a compressor bulb 71 having two open

ends is disposed between the siphon legs 19^a 45 and 19^b having its ends in communication therewith. The ends of these legs which are received in the compressor are each provided with valves 72 and 73 respectively, of the type shown in Figures 2, 3 and 4, both 50 these valves opening downwardly as illustrated. Pressure on the bulb expels the air from the lower arm 19^b, the upper valve 72 closing as shown in Figure 8. The release of the bulb results in the drawing of water 55 thereinto through the valve 72 which now opens because of the suction, the lower valve 73 being closed by the same action (Figure 9). After the suction in the bulb has been released by the complete expansion thereof, 60 and filled with water, the weight of the latter pushes the lower valve 73 open, and a continuous flow is had therethrough by reason of the atmospheric pressure upon the surface of the liquid in the vessel through 65 the vent 20. The upper valve 72 remains open because of the downward flow of water thereon.

Having thus fully described the invention, what we claim as new and desire to protect by Letters Patent is:—

A device for dispensing liquid comprising a lower vessel and an upper vessel having an air vent in its top, a pipe extending upwardly from said lower vessel to substantially 75 the top of the upper vessel, a siphon tube extending from the lower portion of the upper vessel through the top thereof and having its lower leg received within said pipe, a permeable packing between the leg 80 and the upper end of said pipe, and means communicating with said siphon for reducing the pressure in the upper leg thereof.

In witness whereof we have hereunto set our hands.

JOSEPH ALFRED GOYER.
LYNN T. LEET.
